UNITED STATES PATENT OFFICE.

CLARENCE B. FROST, OF CAMBRIDGE, MASSACHUSETTS.

PACKAGE-SEALING DEVICE.

No. 848,734.

Specification of Letters Patent.

Patented April 2, 1907.

Application filed May 15, 1906. Serial No. 316,998.

To all whom it may concern:

Be it known that I, CLARENCE B. FROST, of Cambridge, in the county of Middlesex and State of Massachusetts, have invented certain new and useful Improvements in Package-Sealing Devices, of which the following is a specification.

This invention relates to package-sealing devices.

More particularly, it relates to apparatus for supplying strips of gummed paper or other adhesive fabric in convenient form for use in binding and fastening packages and parcels.

The objects of the invention are to improve and simplify such apparatus in a number of features, among which are the arrangements for delivering adhesive tape from the machine, for retracting tape from the moistening-roller or other means that render it adhesive, for controlling tape-tension and guiding the delivery of the tape from the storage supply in the machine, for delivering a variety of tapes from a single machine, for guarding the severing-knives, and in general to provide improved apparatus in accordance with the principles hereinafter described. These objects are accomplished by the means hereinafter described, and illustrated in the accompanying drawings, in which—

Figure 1 represents a side view of one form of apparatus embodying the invention, the apparatus being represented open with the interior parts exposed to view. Fig. 2 is a plan view, partly in section, of the same. Fig. 3 is an enlarged side view of a portion of Fig. 1. Fig. 4 is an end or front view of a severing-knife and its guard. Fig. 5 is a plan view of certain details of Fig. 3 directly above it.

The invention is not limited to the particular form and construction here shown and described; but the embodiment here represented serves to illustrate the best form in which I at present contemplate constructing the invention. In this form tape is supplied from a roll of previously-prepared gummed and dried paper and is arranged with its forward end projecting from the case. The preparation of the tape by coating one side of the paper with mucilaginous gum and allowing the same to dry renders the tape slightly elastic and capable of becoming adhesive by the addition of moisture. When needed for use, the tape is drawn forth, and

in so doing is moistened, and thus rendered adhesive, and is cut off, leaving an end projecting for future use, and the moistening operation is stopped.

Referring to the drawings, the various parts of the machine are supported by a frame, which is preferably in the form of a closed casing, composed of the two parts 0 and 1, inclosing and protecting the tape and all the parts. The two sections are vertically hinged together at 2 at the rear, each having two legs 3 3. When the two parts 0 and 1 are swung together about the hinge, as indicated by arrows 2' in Fig. 2, the casing stands upright on the four legs, and the same is true when the case is only partly swung together. The case may therefore be conveniently opened to permit examination or readjustment of the interior parts without disturbing the level of water contained therein. The apparatus will supply one or more tapes of varying widths or varying from each other in other respects. When only one tape is to be supplied, all the working parts are preferably supported in the section 1, so that upon opening the casing all the mechanism is open to view on the exposed wall and is easily accessible, the casing meanwhile standing upright self-supported. When two tapes are to be supplied, one may be mounted on the vertical wall of each section, all using a common moistening and delivery device, as hereinafter described. Mounted on the vertical wall of section 1 is a pivot-pin 5, which affords a convenient means for supporting a roll 6 of tape.

In the forward part of the machine is a pan 7, adapted to contain water or other liquid for rendering the tape adhesive. The preferred method is to draw the tape from the roll as needed for use, passing it into contact with a moistening-roller 8, partly immersed in water in pan 7. A storage-reservoir 9 maintains a supply of water, consisting of a receptacle which is entirely closed except a neck 10, which projects downward and opens into pan 7. Water can escape from the reservoir only when air is admitted at the mouth of the neck to take its place, and this happens only when the level of water in the pan falls below the mouth. At such times a little air enters and a corresponding amount of water escapes, thus raising the level in the pan and resealing the mouth with a water seal.

The course of the tape from the supply-roll 6 lies around a guide-roll 11, preferably placed

in the lower part of the casing, over a guide-roller 12; preferably above the level of the moistener, thence under a pin 13, over a pin 14, over the roller 8 of the moistening device, 5 thence issuing from the apparatus between delivery-rolls 15 and 19. Outside and adjacent thereto a severing-knife 16 is rigidly fastened. This knife preferably has a rigidly-mounted V-shaped blade, pointed downward. By raising the tape which has been drawn forth toward the knife the point of the V pierces the tape, and the tape is thus severed, cutting outward from the center toward each edge.

15 One feature of the invention relates to the tension device employed to maintain the tape at proper tension. This consists of a spring 17, mounted rigidly on the pivot 5, on which the roll is rotatably mounted, the 20 spring pressing flatwise upon the end of the roll of tape. A preferred shape of this spring is shown in Figs. 1 and 2. This holds the roll with a uniform tension after the diameter of the roll has been greatly reduced by withdrawal of tape, as well as when the roll is of 25 original size. The spring consists of a simple flat piece, bent outward at its center, where it is pierced by a slot 24, having an enlargement 26 at one end a little larger than the head of the screw. The shank of the screw or the 30 end portion of the pivot-pin is filed flat to fit the slot 24. The spring is mounted by slipping the enlarged hole over the screw-head and then slipping it sidewise, so that the slot 35 and flat shank come together, thus preventing relative rotation. The spring may be adjusted to the desired tension by means of the screw. It is preferred to arrange the parts so that the proper adjustment will 40 occur with the spring in the relative position indicated in the right-hand half of Fig. 1. The spring is longer than the diameter of a full-sized roll, as shown, and by thus projecting beyond it serves as a guide to keep the 45 outer layer of tape in place.

Another feature of the invention relates to the stationary pins 13 14, which serve to guide the tape to the moistening device and also to retract the same therefrom. 50 These are placed in approximately vertical position, one over the other, with the under one preferably a little forward of the upper. They are represented in the drawings as studs, which may be screwed firmly into the side 55 wall of the pan, which is formed high for this purpose, each stud having a thin cylindrical shell 4 loosely mounted thereon, thus forming a roller to reduce friction, held in place by the flanged head of the stud, which also serves 60 as a guide to retain the tape thereon. When the tape is drawn forth, it passes under roll 19, and being held taut by the tension device 17 it tends to be drawn into an approximately straight line, tangent to the top of 65 pin 14 and tangent to the lower surface of

roll 19. This pin and roll are placed in such position with respect to the moistening-roll that the top of the moistening-roll 8 intervenes between them and obstructs this tangential line, thus compelling the tape to be 70 drawn upon the surface of the moistening-roll. Roll 19 is adjustable in position in slot 20. According as it is adjusted to a lower or higher position the tape will be compelled to contact with more or less of the surface 75 of moistening-roll 8, and if raised enough the tape may escape contact altogether. It is one feature of the invention to employ tape having a certain degree of elasticity. After the external end 35 has been cut by knife 16 80 the elasticity of the tape will retract the end 36 a little and will raise the tape a little above its position when being drawn forth, as indicated by the dotted line 36' in Fig. 3, in order to relieve the tape of the torsion or 85 sharp curve caused by the bend from pin 13 around pin 14. The extreme exterior end of the tape is then maintained out of contact with the moistener by resting, if necessary, upon roll 15, and the portion of the tape lying 90 next interior is sprung upward from the moistening-roll by reason of the approximately vertical situation of the pin 14 over pin 13. In prior devices, so far as known to me, it has been necessary to provide some 95 sort of moving carriage "strip-lifter," or other device to lift and move the tape bodily away from the moistening device, or else to move the moistener bodily away from the tape; but by the device here described I 100 cause the tape automatically to move itself away therefrom, so that the tape is not in contact with the moistening device except when actually under the tension in the act of being drawn forth from the machine. 105

Another feature of the invention relates to the external support 15 for the tape. This is preferably a small roll, rotatable upon a stud 21, and having two or more thin ridges 18 on which the tape is supported. This roll is preferably set close to the moistening-roll on the side toward roll 19. The tape ordinarily does not touch it when being drawn forth. To prevent this roll from scraping gum from the freshly-moistened adhesive surface of the tape in case the latter should carelessly be drawn in contact therewith, the working surface of the roll is composed of a series of narrow and rather sharp ridges 18, which are set in planes approximately parallel to the line of travel of the tape. It is found that these do not remove gum from the tape. 110 115 120

Another feature of the invention relates to the guard, which serves the double purpose of preventing the knife from injury and of protecting all persons from being injured by the knife. When the knife is in use, its point penetrates the tape, and hence the knife is surrounded on all sides by the strip of tape. 125 130

The guard must not interfere with the normal working of the machine and must not be in the way of handling a package to which the tape is being applied. In the guard here shown a flat plate 30 is arranged upon the upper or outer side of the knife, overlapping the same in area in all directions, as clearly shown in Fig. 4, and is devoid of sharp corners. This plate has approximately the 10 shape of the knife it guards and is hinged at its upper part, which is the base of the V, to plate 31, which lies upon the shank of the knife, and the plate 31 in turn is hinged to the shank of the knife. The hinge between plates 30 and 31 is set a little back of the knife-corner, as clearly shown in the drawings, plate 30 being bent around the knife-corner for that purpose and set with a slight clearance-space between it and the upper part of 15 the knife, the clearance gradually diminishing toward the point. The plate 30 guards the knife from contact with any object approaching the knife from above, from either side, or from the front; but when the strip of 20 tape is lifted to be severed by the knife, as shown in Fig. 3, the strip automatically removes the guard, lifting the plates 30 and 31, which turn at the hinges 33 and 34 and recede until the tape has been severed, when they 25 fall back automatically by gravity and again 30 guard the knife.

In operation it being assumed that the tape has not been recently moistened, the user touches his finger to the back of the projecting tab of tape 36, pressing this projecting end upon the adjacent moistening-roller 8, and then, releasing it momentarily, presses said end upon the package in hand, to which it adheres. Then by drawing the package 35 away from the machine the tape is drawn forth, the elastic bight 36' above the moistening-roll first being drawn down into contact therewith, so that the tape is freshly moistened as it comes forth. The package in 40 hand is then raised a short distance, as at 37, whereupon the tape encounters the guard of knife 16, raises the guard, and encounters the knife and is severed, as represented in Fig. 3. On being cut the tape end would fall upon 45 the moistening device but for its elasticity or the supporting-roller 15. The elasticity of the tape which has been drawn tight around pin 14 bends its forward portion upward into a bight above the moistening-wheel, as shown 50 by dotted lines 36' in Fig. 3, and thus the tape remains until wanted again for use. The short projecting portion which has been moistened dries with lapse of time, except the part above the roll 15 between it and the 55 top of the moistening-roll, which I have found by experiment remains adhesive for a very long time after the adjacent parts have entirely dried.

Another feature of the invention is as follows: It is desirable for users of this system

of sealing packages to be able to use tape of differing widths, according to the character of the package to be sealed. No method has been known prior to my invention to place two different rolls side by side in the same 70 machine without causing the apparatus substantially to embody two complete separate machines in order that the act of drawing of tape from one roll should not move or affect the other strip of tape. In particular it has 75 not been hitherto possible to accomplish this satisfactorily without providing separate strip-lifting devices, one for each strip of paper, side by side, so that one strip could be moistened without at the same time moistening 80 the other. By the present invention this result is rendered entirely practicable, owing to the fact that movable strip-lifters are eliminated entirely. Two or more rolls of different kinds may be mounted side by side upon the pin 5 and the tape from any one of them pulled into contact with the moistening device without disturbing the adjacent parts of the other strips.

Another application of this principle is 90 shown in Figs. 1 and 2, in which one roll of paper is mounted on the pin 5 and another roll of paper 6' is mounted on the pin 5' in the other section of the frame. Tape from this roll 6' passes around an idler guide-roll 95 11', guide-roll 12', pins 13' and 14', as in the first-described section, the same being duplicates of those first described; but a single moistening and delivery mechanism is used in combination with the two supply mechanisms, and when the two portions of the casing 100 are closed together the tape from roll 6' passes over moistener 8 and between rolls 19 and 15 beside the tape from roll 6.

Many variations may be made from the 105 specific embodiment of the invention here shown and described without departing from the scope of the patent.

I claim—

1. In apparatus of the class described, a 110 holder for a supply of elastic tape; a device for rendering the tape adhesive; a stationary guide for the tape set between the supply and said device, holding the tape normally out of contact therewith.

2. In apparatus of the class described, a 115 holder for a supply of elastic tape; a device over which the tape normally passes for rendering the tape adhesive; two stationary 120 guide-pins for the tape set between the supply and said device, the one above the other whereby the tape normally is directed upward and passes over the said device without contact therewith.

3. In apparatus of the class described, a 125 holder for a supply of elastic tape; a device for rendering the tape adhesive; in combination with a stationary guide set between the supply and said device, holding the tape normally above and out of contact with the de- 130

vice; and a support for the external end outside said device.

4. In apparatus of the class described, a holder for a supply of tape; a device for rendering the same adhesive, over which the tape passes; and a support for the external end of the tape, having ridges approximately parallel to the movement of the tape.

5. In apparatus of the class described, a holder for a supply of tape; a blade rigidly mounted for severing the tape, in combination with a guard for the blade, comprising an adjacent movable plate approximately parallel therewith and projecting beyond its edges.

6. In apparatus of the class described, a holder for a supply of tape; a V-blade for severing the tape, rigidly mounted; in combination with a guard for the blade, comprising an adjacent plate set approximately parallel with the blade and projecting beyond its edges, said plate being arranged to yield toward the base of the V, when engaged by tape about to be severed, thus exposing the blade.

25 7. In apparatus of the class described, a

casing, comprising an inclosing frame having two sections hinged vertically; a supply-holder and guides for tape on each section of the casing-wall; a device mounted on one wall for rendering the tape from both walls adhesive, the guides on the other wall being arranged to guide tape thereto when the sections of the frame are closed.

8. In apparatus of the class described, a holder for a supply of tape, and a moistening device for one surface of the tape, in combination with a layer of elastic adhesive material dried upon said surface of the tape, whereby the tape is rendered elastic, and a non-yielding guide leading the tape to a position adjacent to but not in contact with the moistening device, whereby the unmoistened portion of the tape automatically retracts from said device after contact therewith.

45 In testimony whereof I have affixed my signature in presence of two witnesses.
